(57) **CLAIM**

I claim the ornamental design for a weight training device, as shown and described.

DESCRIPTION

FIG. 1 is a top perspective view of the weight training device design of the present invention;

FIG. 2 is a side elevation view of the weight training device design of the present invention.

FIG. 3 is a top view of the weight training device design of the present invention.

FIG. 4 is a bottom view of the weight training device design of the present invention.

FIG. 5 is a first end view of the weight training device design of the present invention; and

FIG. 6 is the opposite end view of the weight training device design of the present invention.

The broken line portions of the disclosure are for illustrative purposes only and form no part of the claimed design.

1 Claim, 6 Drawing Sheets

FIG. 2

FIG. 5

FIG. 6
